UNITED STATES PATENT OFFICE.

ARTHUR H. MAYNARD, OF WARWICK, RHODE ISLAND, ASSIGNOR TO BOSTON WIRE STITCHER COMPANY, OF AUGUSTA, MAINE, A CORPORATION OF MAINE.

WIRE-STITCHING MACHINE.

1,252,011.

Specification of Letters Patent.

Patented Jan. 1, 1918.

Application filed April 5, 1916. Serial No. 89,205.

To all whom it may concern:

Be it known that I, ARTHUR H. MAYNARD, a citizen of the United States, residing at Warwick, in the county of Kent, State of Rhode Island, having invented certain new and useful Improvements in Wire-Stitching Machines, of which the following is a specification.

My invention relates to wire-stitching or 10 stapling machines for automatically forming staples from a continuous length of wire and inserting them in place to secure together overlapping thicknesses of paper, cardboard or other material. The invention consists 15 particularly in an improved means for adjusting the stitching-mechanism in relation to the work-support, in accordance with the thickness of the work being operated upon; and for also regulating the action of the 20 staple-forming and driving-devices to secure the required length of staple and its proper insertion in conformity with the thickness of the material being stapled or stitched.

My invention contemplates the use of a 25 single means for securing both of these objects; the adjustment of the stitching-mechanism in relation to the work, and the regulation of its action in accordance with the thickness of the work; besides providing for 30 the simultaneous adjustment and regulation of a series of stitching-heads employed in multiple on a gang machine. Certain other improvements in the construction and method of operation of the stitching-mechanism are also embodied in the invention and 35 will be explained hereinafter.

The manner and means for carrying out the improvements are fully described in the 40 following specification, illustrated by the accompanying drawings, in which like reference characters designate like parts. In the drawings:—

Figure 1 is a side elevation of a wire-stitching or stapling machine embodying the 45 present improvement;

Fig. 2, an enlarged, side view of the upper portion of the machine showing the overhanging arm, which supports the stitcher-head, in longitudinal section to illustrate 50 the relation of the stitching-mechanism to the driving-means, and also showing the relation of the stitching-devices to the staple-clenching mechanism;

Fig. 3, a front view of the stitcher-head or

bonnet which carries the staple-forming and 55 driving mechanisms;

Fig. 4, a side view of the same, part sectional on the line 4—4 of Fig. 3, to show the method of attaching the bonnet to the front of the stitcher-arm; 60

Fig. 5, a front elevation of the stitcher-head supporting-means and driving-connections shown in connection with the staple-clenching means;

Fig. 6, a plan view of the supporting 65 means and driving-connections for the stitcher-head; and

Fig. 7, a detail view of the manually-operable means for adjusting the bearing or 70 quill Q for the drive-shaft M;

Fig. 8, a detail view of the arrangement for locking the driver-bar D and bender-bar H together;

Fig. 9, a perspective view of the staple-forming anvil O showing a severed length of 75 wire held therein;

Fig. 10, a detail view of the connection between the reciprocating slide S and the rotary hub U which operates the anvil O;

Fig. 11, a side view of the cam-plate V² 80 which operates the wire cutters V, V'; and

Fig. 12, a front view of the same showing the connection between the cam-plate and the cutters.

Referring first to Fig. 1, I have preferred 85 to illustrate my invention as applied to a machine of usual type such as is now generally known and used in various arts. As here shown the main machine is constructed with a base or pedestal P surmounted by a 90 C-shaped frame P' having an upper, horizontal arm A, on the forward end of which is mounted the stitcher-heads or bonnets B. Hinged to the rear arm of the frame P' is a flat shelf or table T which aligns with a 95 forward extension T', the two parts serving as the work-support for holding the articles to be stapled in position beneath the bonnets B. Preferably, the portion T' of the work-table is pivoted on the forward, upright 100 column p of the frame P' so that it may be adjusted with its side t, t inclined to the horizontal, as shown by the dotted lines, to adapt the machine for saddle-stitching. When the work-support T' is employed in 105 this manner the rear shelf T is lowered out of the way as also shown by the dotted lines in Fig. 1.

Extending through the horizontal arm A at the top of the frame P' is the main drive-shaft M for the machine, see Fig. 2, carrying a belt-pulley M' at its rearward end. Preferably the pulley M' is connected with the shaft M by means of a suitable clutch-device, not here shown, which may be operated from a foot-treadle in the usual manner. At its forward end the arm A is formed with a vertical plate or flange a to which is bolted an upright frame F constructed with a horizontally-extending rail R projecting some distance at either side. The rail R serves as a support for the stitcher-heads or bonnets B and is adapted for attaching a plurality of these on its front face to provide a multiple or gang machine. For certain varieties of work the supporting rail R is sometimes mounted on the frame of a printing-press, folder, binder or other type of machine, to adapt the stitching-mechanisms of the heads to operate in conjunction with the operation of printing, folding or binding the leaves of booklets, pamphlets or the like. That is to say, my improved mechanism, although being herein shown and described in connection with a stitching-machine complete in itself, is also adaptable for use with other mechanism for various classes of work.

Referring to Fig. 5, the frame F as here shown comprises two spaced uprights f, f and the lower, horizontal rail R, in the front face of which is formed a longitudinal T-slot r. Fitted to slide in the T-slot r are blocks E, E which serve as clamping-means for securing the bonnets B in place, one block being provided for each head used. While I have here illustrated two of the blocks E in place, it will be sufficient to describe the connections for one head only as the arrangement and construction of all of them is identical. Likewise, the complete staple-forming and driving mechanisms contained within the bonnets B are all the same in construction and have the same method of operation and therefore only one will be described, it being understood that as many individual heads as required may be used on one machine in accordance with the character of the work to be performed.

Referring to Figs. 2, 3 and 4, the stitcher-heads or bonnets B consist of narrow, trough-like casings or boxes having parallel sides b, b formed with rearwardly projecting portions at their base, as shown particularly in Fig. 4. The rear wall b' of the lower portion of each bonnet B is adapted to fit against the front face of the supporting-rail R and is provided with an opening b² located opposite the slot r. Projecting forwardly from the block E into the opening b² is a stud e flattened off on its upper side and formed with a transverse, beveled slot e', see Figs. 4 and 5. Journaled in the sides b, b of the bonnet B and extending

across the opening b² in the wall b' is a rod or pin g cut away at its center to form a half-round, eccentric portion g'. Secured to one end of the pin g is a finger-lever G, see Fig. 2, positioned at the side of the bonnet B and adapted for manual operation to rotate the pin. The forward portion of the block E fits into a cross-slot b³ on the back of the bonnet B to locate the latter vertically on the rail R and when the lever G is raised the flat portion of the eccentric g' will be turned to allow the stud e to slide in under the pin g. After the bonnet B has been adjusted in position on the rail R the lever G is turned down into the position shown in Fig. 2, and the rounded portion of the eccentric g' will then be carried into wedging engagement with the forward, beveled side of the slot e' of the stud e. This action causes the block E to be drawn forward in the slot r to lock it in place and to also clamp the bonnet B firmly against the rail R to bind it in position thereon. In this manner the bonnets B may be attached rigidly to the front of the rail R while allowing for their lateral adjustment in relation to each other and with respect to the work to be operated upon.

Referring now to Figs. 3 and 4, the staple-forming and driving mechanisms carried in the bonnets B is of substantially the same construction and arrangement as that shown and described in United States Letters Patent No. 970,461, granted Sept. 20, 1910 to Thomas A. Briggs. They comprise essentially a wire-feed for feeding the wire down through the machine, a rotary anvil for receiving and holding the wire, cutters for severing it into lengths, a bender-bar for bending over the legs or sides of the staple, and a driver for inserting the staples through the work, all arranged and organized as next described. Formed on the inner faces of the parallel sides b, b of the bonnet B are opposite, vertical grooves b⁴, b⁴ in which the several reciprocating parts of the staple-forming and driving mechanisms are fitted to slide. The main actuating-member for the reciprocating elements consists of a block or slide S formed on its sides with splines s, s engaging the grooves b⁴, b⁴. Beneath the slide S is the staple-former or bender-bar H also formed with splines h, h fitted to slide in the grooves b⁴, b⁴ and carrying the wire-feed K on its front. The bender-bar H is connected to be reciprocated from the slide S by means of the driver-bar D which is also adapted for movement independently of the bender-bar. As shown most clearly in Fig. 8 the bender-bar H is formed with opposite, parallel sides h', h', connected by a web h² at the back, and extending down in the legs h³, h³ which co-operate with the forming-anvil to bent over the legs of the staple as later described. On

the inner sides of the legs h^3 , h^3 are grooves h^4 , h^4 for receiving the opposite, parallel legs of the staples after they have been bent over as hereinafter described. The driver-bar D is fitted to slide between the sides h' , h' of the bender-bar H and is held in place by a cross-member or cleat k which forms a part of the wire-feed K and is riveted to the front of the bar H. At its lower end the driver-bar D carries the driver proper consisting merely of a flat plate D' let into its front face and held in place by suitable means, not here shown or described in detail. At its top the driver-bar D is provided with a recess on its rear face which forms a shoulder d' adapted to be engaged by a forwardly-projecting lip s' at the bottom of the slide S, see Fig. 4. Engaging the upper edge of the driver-bar D is a plunger-pin s^2 fitted to the lower end of a vertical bore s^3 in the slide S. A coiled spring s^4 held under compression in the bore s^3 by a screw s^5 bears against the pin s^2 to normally maintain it pressed against a retaining shoulder s^6 at the bottom of the slide S. This arrangement provides a yielding connection between the driver-bar D and the operating-slide S so that when the driver D' and bender-bar H are forced down against the work they will not be bent or broken should the material being operated be of excessive thickness, that is of greater thickness than what the machine is set for. Through this provision the parts are prevented from injury should the operator inadvertently or carelessly insert too many thicknesses of material into the machine.

Referring again to the detail view, Fig. 8, one side of the driver-bar D is formed with a slot d^2 having a lower, square shoulder d^3 and an upper, square shoulder d^4 of less depth. Between the shoulders d^3 — d^4 is a projection or lug d^5 beveled off on its opposite sides at d^6 , d^7 . Mounted to slide in a lateral slot k' cut through the cleat k, see Fig. 4, is a latch or key-member K' fitted over the bar D and formed on its rear face with a lug k^2 adapted to engage the shoulders of the slot k^2 therein. The key K' is normally held in the position illustrated in Fig. 8 by means of a wire spring k^3 fastened in a slot on the back of the bender-bar H and having its upper end k^4 bent forward and reaching out through a hole k^5 . The latch K' serves as a means for positively locking the driver-bar D to the bender-bar H to cause the latter to be forced downward by the slide S. The bender-bar H is normally moved in the bonnet B through a friction connection between it and the driver-bar D. Referring to Fig. 4, a coiled spring i held in a pocket in a stud I screwed into the back of the bender-bar H acts on a friction-plug i' to press the latter against the rear face of the driver-bar D. Through

this means the driver-bar D and bender-bar H are held together with sufficient friction to normally cause the latter to be moved with the former, but in forcing the bender-bar H against the staple a positive action is provided through their direct connection as more fully explained hereinafter.

As shown in Fig. 3, the front face of the cleat or wire-feed member k is recessed to form a ledge k^6 along which the wire w draws as it leads down from the top of the machine. Mounted to slide in a horizontal slot k^7 formed in the side of the cleat k is a T-shaped grip-member J having its vertical edge serrated or formed with the teeth j adapted to bear upon the wire w to press it against the ledge k^6 on the cleat k. The end k^8 of the wire spring k^3 extends through a hole j' in the grip J and tends to press the serrated jaw j against the wire. Referring particularly to Figs. 3 and 8, the operation of the latch K' and wire grip J is controlled by means of a slide L held in a slot b^5 in the side b of the bonnet B and extending upwardly to the top thereof. At its lower end the slide L is cut away along its inner side to provide a slot l in which the right-hand end of the latch K' rides. At its bottom is a beveled shoulder l' against which the lower, beveled side of the latch K' strikes to force the latch to the left to release the pressure of the wire-spring k^3 and relieve the grip J from the wire w at the end of the feeding stroke, all as more fully explained hereinafter.

On the front of the bonnet B is a face-plate B' having its edges fitted to grooves b^6 , b^6 in the sides b, b and held in place by spring-clips b^7 , b^7 formed with shoulders overlapping its sides. At its lower end the plate B' is cut away to provide a rectangular opening b^8 through which the wire-feed block or cleat k projects to adapt the latter to strike against the top edge thereof to limit the extent of its upward movement. The plate B' is adjustable up and down in the slots b^9 , b^9 and may be set in different positions to control the range of action of the wire-feed K so that the latter is regulated to feed the proper length of wire in accordance with the length of staple required. The adjustment of the plate B' also serves to adjust the position of the slide L which releases the wire-grip J at the lower end of the feeding stroke. At the top of the bonnet B is a block B² fitted between the sides b, b and clamped in place by a screw b⁹ extending through it. In the top of the block B² is a screw b¹⁰ having its head positioned in a recess b²⁰, cut into the side of the block, see Fig. 3, to adapt it to bear against the top of the bonnet B. By turning the screw the block may be adjusted vertically in the bonnet for a purpose as later described. Pivoted on the front of the block B² by means

of a stud l^3 is a lever L' , one end of which engages a slot l^4 in the release-slide L . The opposite end of the lever L' is slotted at l^5 to receive a stud or pin b^{10} projecting rearwardly from the plate B' . Through this connection the movement of the plate B' up or down in its slots in the bonnet B will effect a relative movement of the release-slide L in the opposite direction. When the plate B' is raised in the bonnet it will allow the wire-feed K to make a longer stroke upward and will also adjust the slide L to cause the wire-grip J to be released at a lower point in its downward stroke so that in this way the adjustment is compounded. In other words, less movement of the plate B' is required to lengthen the operative stroke of the wire-feed and increase the length of the staple than if only one of the parts were movable. The vertical adjustment of the plate B' is controlled by means connected with the adjusting devices for the staple-driving mechanism of the machine as later described.

The wire w is fed down by the grip-device K to a rotary anvil O , before mentioned, which is similar in construction and method of operation to that described in the patent above referred to. As shown in Figs. 3 and 4, an arm O' extends outwardly from the side of the bonnet B near the bottom thereof and is formed with a circular bearing or brushing o at its end. Mounted to rotate in the bearing o is the cylindrical anvil O formed with a head or flange o' at its outer end which normally abuts the end of the bearing to locate the anvil longitudinally therein. The inner end of the anvil O is beveled off with a conical point or nose o^2 formed with diametrical slots o^3 , o^4 extending across it at right-angles to each other. The slot o^3 is somewhat deeper than the slot o^4 and receives the wire w as it is fed down by the feed-device K on the bender-bar H . As the wire w is held in a vertical position while being fed by the wire-feed K , the anvil O is rotated through an angle of ninety degrees and this causes the wire to be brought into the shallower slot o^4 . Then as the anvil O is turned back again to its first position the length of wire w for the staple, after being severed by cutters as later described, is turned with it and brought into a horizontal position in under the bender-bar H with its ends projecting from the sides of the anvil directly beneath the forming-legs h^3 , h^3 . A wire spring o^6 is secured in an axial hole in the anvil O with its end projecting therefrom to adapt it to bear against the length of wire w held in the slot o^4 to retain it in place therein while the anvil is being rotated, see Fig. 9. The method of operation of this part of the mechanism is fully described in the

patent above referred to and explained more in detail hereinafter. In the present arrangement the rotation of the anvil is effected by an improved and simplified mechanism, somewhat different from that shown in the previous patent, as next described:

As shown in Figs. 3 and 10 the means for rotating the anvil O consist of a Geneva-motion, so-called, operated from the reciprocating movement of the slide S . Pivoted eccentrically on a pin u projecting from the front of the bonnet B is a hub U carrying a crank-pin u' on its front face. Connected to the crank-pin u' is a link U' carrying a crank-pin u^2 at its lower end inserted in a hole in the head of the anvil O . Preferably the link U' is constructed of flat spring-metal and is bent or bowed inwardly toward its lower end to cause it to exert a pressure against the end of the anvil O . This pressure tends to maintain the anvil O with its flange or head o' seated against the end of the bearing o while also allowing the anvil to be retracted in its bearing for a purpose as later described. Referring now to Fig. 10, the inner end of the crank-disk U is flattened off to form two shoulders u^3 , u^4 arranged at right-angles to each other and adapted to be engaged by the side of a projecting shoulder or ledge s^7 on the front of the reciprocating slide S , see also Fig. 3. The shoulder s^7 is cut away with an arcuate slot at s^8 and opposite this is a pin s^9 projecting forwardly from the front face of the slide S . The pin s^9 is adapted to enter a radial slot u^5 in the crank-disk U to turn the latter as the slide S descends in the bonnet B . With the slide S at the upper end of its stroke, as shown in Fig. 3, the shoulder u^3 of the crank-disk U engages its shoulder s^7 and is thereby restrained from turning during the first part of the movement of the slide. As the slide S descends its pin s^9 will enter the slot u^5 in the crank-disk U , see Fig. 10, and the curved slot s^8 will allow the latter to rotate until its shoulder u^4 brings up against the upper portion of the shoulder s^7 on the slide. At this juncture the pin s^9 passes out of the slot u^5 and the disk U is locked from further rotation until the slide S returns upwardly again. In this manner the crank-disk U is given an intermittent, rotary motion in opposite directions through an angle of ninety degrees and an equal motion is imparted through the link U' to the anvil O , with both elements locked in position at the opposite extremes of their movement.

Fastened on the front of the face-plate B' at its lower end is a guide or support B^8 for the wire-cutters V , V' . These consist of two bars formed with sharpened ends and

arranged with one bar V held fast in the guide B³ and the other bar V' adapted to slide therethrough. As shown in Fig. 12 the fixed cutter V is formed with a projection v on its front which fits an opening in the front of the guide B³ to hold it in place therein. The end of the cutter V projects beyond the side of the guide B³ and is slotted across its front to provide a sharpened edge 10 v'. The movable cutter V' slides in the guide B³ below the cutter V and is formed with an inclined end having a sharpened edge v² at its top. Projecting from the rear of the sliding cutter V' is an inclined lug v³ 15 adapted to engage a cam-groove v⁴ in a vertical plate V². The plate V² is arranged to slide between the side b of the bonnet B and the side of the bender-bar H and is held in place by the face-plate B'. The plate V² 20 is adapted to be held frictionally to prevent unwarranted movement by a plug v⁶ pressed against its rear face by a coiled spring v⁷ located in a pocket in the side of the bonnet B, see Fig. 11. At the upper end of the 25 plate V² is a rearwardly-projecting lug v⁸ adapted to be engaged by the lower end of the spline s on the slide S to carry the plate downward, while the top of the spline h on the bender-bar H engages with the lug v⁸ to 30 slide the plate upward in the bonnet. As the plate V² is moved downward at the end of the stroke of the slide S its cam-groove v⁴ acting through the lug v⁸ will slide the movable cutter V' across the path of the wire w, 35 and coöperating with the fixed cutter V will sever the wire at this point. After the wire is severed and the staple formed and driven into place as later described the upward stroke of the bender-bar H will raise the 40 slide V² to retract the cutter V to allow the wire to again be fed down to the anvil O.

Referring to Fig. 4, the bender-bar H carries a staple-supporter X hinged to its rear side and adapted to hold the staple in place 45 while it is being driven down through the work. This element may be of any preferred construction and as here shown comprises an arm x pivoted at its upper end on a cross-pin x' and formed at its lower end 50 with the staple-receiving block x². Projecting from the sides of the staple-supporter are pins x³ adapted to ride on the inclined faces b¹¹, b¹¹ of cam-blocks b¹² formed on the sides b, b of the bonnet B. At the lower 55 end of the bonnet B is a pivoted arm Y carrying a roll y at its lower end over which the staple-supporter rides as it descends with the bender-bar H. The arm Y is engaged by the end of a spring y' pocketed in a stud y² and is limited in its movement under action of the spring y' by a projection y³ on its upper end which strikes against a pin y⁴. As the staple-supporter X descends, its rear beveled face x⁵ rides across the roll y and 60 forces it outward to bring it into place be-

tween the legs of the staple which are held in the grooves h⁴, h⁴ in the legs h³, h³ of the bender-bar H. When the driver-bar D descends its lower edge will ride along the inclined outer face x⁶ of the supporter X and force it rearwardly out of the way against the action of the spring y'. After the staple has been clenched in place and the bender-bar H slides upward in the bonnet B the supporter X is carried back out of the way 70 by its pins x³ riding along the beveled sides b¹¹ of the cam-blocks b¹² as before described.

As previously stated the plate B' which regulates the stroke of the wire-feed K and thereby the length of the wire which is cut 80 off to form the staple is adjusted by a means which also controls the operative position of the bender-bar H and driver-bar D in relation to the work being operated upon. This means is coördinated with the main 85 drive-shaft M of the machine as shown particularly in Fig. 2, and is arranged to act universally in connection with a plurality of heads B mounted on the supporting-rail R. The shaft M is journaled in a sleeve or quill 90 Q which extends the length of the arm A and is mounted in bearings a², a³ at each end thereof. At the rearward end of the quill Q the shaft M extends through a bearing q arranged substantially concentric with the 95 bore of the bearing a² in which the quill sets. At its forward end, however, the bearing q' for the shaft M is bored eccentric to the bore of the front bearing a³ in which the quill sets. In other words, the axis of the 100 shaft M at the forward end of the quill Q is offset from or out of alignment with the axis of the quill itself. This provides that when the quill Q is rotated in its bearings in the arm A it will cause the forward end 105 of the shaft M to be raised or lowered slightly from the horizontal, the object being to adjust the position of the parts connected with the shaft in relation to the work to be operated upon by the stitching-devices. 110 The shaft M being operatively connected to the staple-forming and driving devices as later described, it is obvious that any adjustment in its position will also serve to adjust these parts up and down relatively to the 115 work on the fixed table below the bonnets B.

Formed on the rear end of the quill Q is a vertical arm Q' beveled off at its top and carrying a handle Q² screwed into its end. Fastened to the end of the quill-bearing a² 120 by means of the countersunk screws q¹ is a semi-circular plate or disk-like sector Q³, see Fig. 7, having a beveled edge alining with the end of the arm Q'. A washer q⁵ on the threaded portion of the handle Q² 125 overlies the edge of the sector Q³ and is adapted to be clamped thereagainst by screwing the handle into the arm Q'. The handle Q² provides a convenient means for turning the quill Q in its bearings and the 130

washer q^5 serves for locking the arm Q' in place after the shaft M has been adjusted to the position desired.

Fast on the forward end of the shaft M is a crank-disk M^2 from the front of which projects a crank-pin m , see Figs. 2 and 5. The crank-disk M^2 serves as the driving-means or prime-mover for reciprocating the slide S in the bonnets B and is connected therewith through a means which is universally adaptable for operating the stitching-mechanisms of any number of bonnets arranged on the rail R . As shown particularly in Figs. 4, 5 and 6, the connecting-means between the crank M^2 and the slides S of the several bonnets comprises essentially a rectangular plate or cross-head N extending across the machine parallel with and above the rail R and adapted to reciprocate up and down on the frame F . Fastened to the uprights f, f of the frame F or formed as a part thereof are two parallel arms or guides F', F' , see Figs. 4 and 5, having vertical grooves f^2, f^2 on their inner sides. Fastened to the back of the cross-head N are two vertical rack-bars n, n having tongues or splines n', n' fitted to slide in the grooves f^2, f^2 of the guides F', F' . The inner faces of the rack-bars n, n are formed with teeth n^2 adapted to mesh with the teeth of two pinions n^3, n^3 on the opposite ends of a cross-shaft n^4 journaled in bearings in the arms F', F' . Through this arrangement the movement of the cross-head N is equalized at its ends so that there will be no tendency for the splines n', n' on the bars n, n to cramp in the guiding-grooves f^2, f^2 . Referring particularly to Figs. 2 and 5, the crosshead N is connected to be reciprocated from the crank-disk M^2 by means of a link or connecting-rod N' one end of which is pivoted on the crank-pin m and the opposite end on a pin m' projecting from the rear of the crosshead. On the lower edge of the crosshead N is a ledge n^5 extending clear across its front face and formed with a horizontal slot n^6 . Projecting from the rear face of the slide S , near its upper end, is a pin s^{10} flattened off on opposite sides to adapt it to enter the slot n^6 in the crosshead N . It will be understood that each slide S is provided with a pin s^{10} for connecting it with the crosshead N and in this way the operating mechanisms in all of the bonnets B are adapted to be driven from the crank M^2 on the shaft M . This form of connection between the stitching-mechanisms and the driving-means provides for operating any number of heads from one drive-shaft and also allows for the adjustment of the heads laterally on the rail R .

It will be understood from the foregoing description that by adjusting the forward end of the drive-shaft M up or down in

the arm A the crosshead N connected with the crank-disk M^2 will also be adjusted in vertical position. Through this means the slides S and their connected parts in the bonnets B may be adjusted in relation to the work to be operated upon as more fully explained hereinafter. The adjustment of the shaft M is also arranged to coincidently adjust the face-plates B' on the bonnets B to regulate the stroke of the reciprocating wire-feed K in accordance with the length of staple required. The means for effecting this second adjustment are as follows: Referring to Fig. 2, the outer end of the quill Q is formed with a circular bearing q^6 80 formed eccentric to the portion of the quill which seats in the bearing a^3 in the arm A but concentric to the axis of the shaft M . Surrounding the bearing q^6 is an arm or slide Z which reaches up through a vertical slot f^3 in the frame F and carries a forwardly extending lug z at its top. Fastened to the front of the lug z by means of a stud z' is a vertical plate or rail Z' having a horizontal slot z^2 extending along 85 its lower edge. The slot z^2 is adapted to be engaged by a lug b^{13} which projects rearwardly from a block B^4 arranged to slide up and down in the bonnet B and guided by splines b^{14} fitting the grooves b^4, b^4 in 90 the sides b, b , see Figs. 3 and 4. The block B^4 is connected with the face-plate B' which adjusts the stroke of the wire-feed by a pin or stud b^{15} . As shown in Fig. 4 the pin b^{15} is fitted to a bore in the block B^4 100 and is held in place by a set-screw b^{16} . The head b^{17} of the pin b^{15} fits a hole b^{18} in the face-plate B' and is preferably formed eccentric to the body of the pin so that by turning the latter the relation between the parts may be altered within certain limits. That is to say, when the pin b^{15} is turned in its bearing the plate B' will be adjusted up and down in relation to the block B^4 . A further adjustment between the plate B' 110 and the adjusting quill Q is provided by the stud z' which connects the plate Z' with the arm Z . As shown in Fig. 4 the head z^3 of the stud z' which engages a hole in the plate Z' is formed eccentric to the portion of the stud which is mounted in the lug z of the arm Z . By turning the stud z' the plate Z' may be raised or lowered on the arm Z . By means of these two adjustments the face-plates of the several heads used on the machine may all be set in proper relation to give a uniform length of stroke to the several wire-feeds K . It will be understood from the above that the cross-plate or rail Z' is raised or lowered to simultaneously adjust the positions of the face-plates B' on the bonnets B when the quill Q is turned to adjust the height of the forward end of the drive-shaft M . To provide for a parallel movement of the plate from 120 125 130

the slide or arm Z, I employ equalizing arms Z², Z² mounted on the ends of a cross-shaft z⁴ which is journaled in bearings in the side arms F', F', see Figs. 4, 5 and 6. The arms Z², Z² carry studs z⁵, z⁵ at their outer ends which project through holes z⁶, z⁶ in the plate Z'. Only a slight, vertical movement of the plate Z' is necessary for the adjustment of the face-plates B' and the studs z⁵, z⁵ have a clearance in the holes z⁶, z⁶ to allow a limited amount of play so that the plate is not thrown out of its vertical position.

In some types of machines the staple-forming and driving mechanisms are arranged to operate in connection with a fixed clencher-block which acts to clench the legs of the staple in place after they have been inserted through the work. In other cases oscillating clencher-levers are employed to bend the legs of the staple into place and the present machine is adapted for either arrangement. In the drawings I have preferred to show the machine as complete with movable clenches for coöperating with the mechanisms in the stitcher-heads B. Referring to Figs. 1, 2 and 5, a rectangular, box-like frame C is mounted on the top of the forward column p of the frame P' and between its sides is a rockable frame C' pivoted on the shaft c. Connected to the forward end of the frame C' is a link c² pivotally joined at its lower end to a horizontal lever C² fulcrumed at c⁴ on the main frame P' of the machine, see Fig. 1. Extending upwardly from the rear end of the lever C² is an arm c⁵ carrying a block or roll c⁶ at its upper end. The roll c⁶ is engaged by a cam C⁸ fast on the drive-shaft M whereby the rotation of the shaft imparts a rocking motion to the lever C² to oscillate the frame C' in a manner as well known and generally employed in machines of this type. The upper portion of the frame C is formed with a vertical front face c⁷ scored along its length with a horizontal T-shaped slot c⁸, see Fig. 2. Fitted to slide along the front face c⁷ are a series of plates or clencher-supporters c⁹ having tongues c¹⁰ on their rear faces fitted to the slot c⁸. Fitted to slide in the slot c⁸ at the rear of the tongues c¹⁰ are T-headed pins or studs c¹¹ reaching through holes in the plates c⁹ and threaded to receive the nuts c¹² on their outer ends. Two studs c¹¹ are provided for each clencher-plate c⁹ and by tightening their nuts c¹² they may be clamped in place in any position to which they may be adjusted along the frame C. Pivoted at the top of the plates c⁹ are the clenches c¹³ which consist of pairs of rockable levers adapted to be pressed up against the legs of the staple to bend them in place against the under side of the work. The clenches c¹³ are of usual construction having openings c¹⁴ engaged

by the rearwardly projecting lip c¹⁵ of a slide c¹⁶ mounted to reciprocate on the front of the plate c⁹ and held in place and guided by the nuts c¹² and a cleat c¹⁷, see Fig. 5. At their lower ends the slides c¹⁶ are formed with rearwardly projecting lips c¹⁸ adapted to enter a horizontal slot c¹⁹ in the front of the oscillating frame C' from which they derive their motion. Through these connections the clenches c¹³ are operated intermittently to coöperate with the staple-driving devices in the bonnets B and it is to be noted that the several sets of clenches may be adjusted laterally in position on the frame C in accordance with the position of their respective bonnets without altering the driving-connections. Any required number of sets of clenches may be applied to the machine in accordance with the number of heads or bonnets B being employed and the capacity of the machine is only limited in this respect by the length of the rail R and frame C. That is to say, the parts for supporting the stitcher-heads and their associated clencher-mechanisms may be extended within reasonable limits to adapt the machine for work of considerable breadth or for a multiple series of separate pieces of work as on a printing-press, folder or binder.

The method of operation of the complete machine is as follows: In installing the machine for use as many heads or bonnets B are attached to the rail R as required for the work in hand. For instance, in stapling calendar pads to cards, stitching signatures for booklets, or for similar work two, three, four, or any number of staples may be inserted simultaneously by providing the required number of heads B on the machine, and the staples may be set with any desired spacing by adjusting the heads laterally in relation to each other. After the heads have been set in position the hand-levers G, see Fig. 2, are turned down to clamp them in place on the rail R by means of the blocks E as previously explained. In adjusting the stitching-mechanisms to the work in conformity with its thickness the sheets of material to be stitched or stapled together are placed on the work-support T' and the shaft M is then turned by hand to bring the bender-bar H and driver D' down to their lowermost position. The quill-handle Q² is then turned to rotate the quill Q and adjust the position of the shaft M so that the lower ends of the bender-bar and driver will be set down against the work with a slight pressure thereon. After this adjustment is completed the handle Q² is screwed into the arm Q' to bind the washer q⁶ against the edge of the sector Q⁸ and the quill Q will thereby be locked in position against accidental displacement. The blocks B² are next adjusted in vertical position in the bonnets B, by means of their screws b¹⁹ to set the levers L' 130

to provide for the proper positioning of the plates B' and slides L in relation to the forming-anvil O . This adjustment regulates the extent to which the wire w will be fed down through the anvils O so as to equalize the ends of the severed length w' projecting therefrom whereby both legs of the staple will be bent to the same length. The face-plate B' of the several bonnets B 10 are now adjusted by means of their eccentric studs b^{15} , see Fig. 4, to regulate their position in relation to the blocks B^4 and the plate Z' so that they will all be set to allow a uniform length of stroke of the wire-feed 15 K as later described. At the same time the plate Z' is adjusted vertically by means of the eccentric stud z' at the top of the arm Z , see Fig. 2, to regulate the length of the stroke of the wire-feed to provide for the 20 required length of staple in proportion with the thickness of the work to be stitched. It will be understood, of course, that these adjustments for regulating the relation between the plate B' and its coöperating parts 25 are only made once, usually when the machine is first assembled, and thereafter the adjustment of the quill Q to set the bender-bar H and driver D' also acts through the arm Z to regulate the position of the plate 30 B' in conformity with the thickness of the work. That is to say, after the machine has once been set with its parts in their proper relation only a single adjustment is necessary to regulate the action of the coördinated mechanisms for different thicknesses 35 of material to be stapled. This adjustment is made by setting the handle Q^2 , as before explained, and serves to simultaneously adjust the mechanisms of the whole series of 40 heads B on the rail R .

Power is applied to the machine through the driving-pulley M' and when the clutch is thrown in the shaft M will be rotated to turn the crank-disk M^2 . The crank M^2 acts 45 through the connecting-rod N' , see Figs. 2 and 5, to reciprocate the crosshead N which slides on the guides F' , F' , with its motion maintained parallel by the rack-bars n , n . From the crosshead N a reciprocatory motion is imparted to the several slides S in the series of bonnets B . As the arrangement of the stapling-mechanisms is the same in all of the heads B it will suffice to explain the method of operation of one of them only. 50 Referring first to Fig. 1, the wire w for the staples is supplied from spools W rotatively mounted on the top of the frame F and thence it leads over curved guides W' and down across the face-plate B' of each bonnet B . Usually means for straightening the wire are provided at the top of the plate B' , but these are not here shown as they form no part of the present invention. As shown particularly in Figs. 3 and 4 the wire w is 55 drawn down through the feeding-device K

and thence between the cutting edges of the cutters V , V' to the forming-anvil O .

With the bender-bar H at the upper end of its stroke as shown in Figs. 3 and 4, the latch K' will be projected to the right with 70 its end in the slot l of the slide L and the wire grip J will consequently be forced by the spring k^3 against the wire w to clamp the latter against the ledge k^6 on the cleat or block k . Referring now to Fig. 8 which 75 also shows the bender-bar H and driver-bar D at the upper end of the stroke, it will be noted that the lug k^2 on the latch K' is in the lower end of the slot d^2 of the driver-bar in its deeper portion with its upper, beveled shoulder d^6 in contact with the beveled shoulder d^5 of the lug d^5 . Now, as the slide S starts to descend the driver-bar D is carried down with it and the engagement of these shoulders combined with the friction action 80 of the plug i , see Fig. 4, causes the bender-bar H to be moved downwardly in the bonnet B . The wire-feed K , as before stated, has taken a grip on the wire w and consequently the wire will be drawn down and fed 85 to the anvil O . On the first descent of the slide S and its connected parts the wire w is fed through the slot o^3 in the end of the anvil O and is afterward severed by the cutters V , V' which are actuated from the cam- 90 plate V^2 at the end of the stroke of the slide S , as previously explained. It has also been explained that as the slide S approaches the end of its downward stroke the pin s^9 in its front engages the slot u^5 in the hub U , 95 see Fig. 10, to rotate the hub which, through its link U' , turns the anvil O in the direction indicated by the arrow 3, Fig. 3. This turning movement of the anvil O takes place 100 before the wire is severed by the cutters V , V' and therefore the lower end of the wire is still held in a vertical position to cause 105 it to ride across the beveled faces o^6 of the anvil O as the latter is retracted in its bearing o . The longitudinal retraction of the 110 anvil O is effected by the driver D' riding across its beveled end and after the anvil has reached the extent of its rotary movement through an angle of ninety degrees its shallow slot o^4 will have assumed a vertical 115 position. The end of the wire w being still unsevered from the main length and being therefore held vertical will thus be caused to snap into the groove o^4 of the anvil O where it is held by the spring clip o^6 shown 120 in the detail view, Fig. 9. As soon as the wire w is thus seated in the groove o^4 the anvil O ceases to rotate, and at this juncture the last end of the movement of the slide S causes the cutters V , V' to act to sever it. 125 In other words, the anvil O comes to rest for an interval while the length of wire w' from which the staple is formed is being cut off from the main piece, and as soon as this 130 is accomplished the slide S starts to move

upward again. After the slide S starts to ascend the hub U will be turned to rotate the anvil O in the opposite direction from that indicated by the arrow 3, Fig. 3, and continuing its movement will turn the anvil back to its original position. This reverse rotation of the anvil O will therefore carry the severed length of wire w' held in its slot o^4 into a horizontal position, as shown by full lines in Fig. 9, while the slot o^3 is being returned into vertical position to receive the next length of wire fed downward. As the driver D' ascends with the driver-bar D it allows the anvil O to be forced longitudinally forward by the action of the spring link U' until the severed length of wire w' which it carries in the slot o^4 is brought into position directly beneath the bender-bar H. Now, as the bender-bar descends again its legs h^3 , h^3 are brought against the ends of the severed wire w' which project from the sides of the anvil O to bend them down at right-angles to the mid portion of the wire held in the slot o^4 . In this manner the opposite, parallel sides or legs of the staple are bent into position to be received in the grooves h^4 , h^4 of the bender-bar H. After the bender-bar H has been carried down to bring the lower ends of its legs h^3 , h^3 against the work, its further movement is resisted thereby and the driver D starts to descend within the bender-bar H. Meanwhile the staple-supporter X has swung out into position between the legs h^3 , h^3 of the bender-bar H to support the staple above the work while guiding its legs as they are driven down therethrough. It is to be understood that the coaction of these parts is essentially the same as that of the mechanism described in the patent to Briggs before referred to wherein a more detailed explanation is given.

The staple being held in the bender-bar H with its ends or driving-points in contact with the work the action of the driver D' is to force it through the work while the clenchers c^3 are carried upward through the work-support T' to bend the legs over and clench them in place. These operations are carried out in the usual manner with the movement of the clencher-operating means synchronized with that of the driving-mechanism through their connection with the main driving-shaft M. As the driver D' is carried down its lower edge forces the anvil O rearwardly in its bearing o so that the formed staple held in the bender-bar H rides out of the slot o^4 . Finally, the grooved, lower edge of the driver D' comes into action against the top of the staple to drive it down and out of the bender-bar and through the material being stitched. It will be understood that the action of the driver bar D is continuous, but that first it moves the bender-bar H down through friction and then when

the latter strikes the work it drives the driver D' positively as the latter slides between the legs h^3 , h^3 of the bender-bar. As the drive-bar D approaches the end of its descent the right-hand beveled end of the latch K' rides against the bevel l' on the side of the slide L and this forces the latch back to release the gripper J from the wire w . It will thus be seen that through the adjustment of the slide L up and down in the bonnet B the wire-grip K may be released at a point commensurate with the length of wire to be fed for any given length of staple. It has been explained that the slide L is adjusted from the movement of the plate B' and that the position of the opening b^8 in the plate regulates the upward extent of the stroke of the wire-feed K. Through the correlation of these parts the operative stroke of the wire-feed K and the position of the cutters V, V' is controlled in accordance with the length of wire required for the staple, and this adjustment is effected at the same time that the position of the stitching-mechanism is adjusted in relation to the work. In other words, the single adjustment of the position of the driver-shaft M through the means of the handle Q² serves to regulate the downward limit of the stroke of the driver D' and also acts to adjust the feed of the wire, the point of severance thereof, and thereby the length of the staple in conformity with the thickness of the stock being operated upon.

After the staple has been driven through the work and its legs clenched in place the slide S starts to ascend carrying with it the driver-bar D and bender-bar H. Referring to Fig. 8, during the last part of the downward stroke of the driver-bar D the lug d^5 on its side rides under the beveled lug k^2 on the back of the latch K' and the latter finally seats in the upper end of the slot d^2 against the shoulder d^4 . It has been explained that this end of the slot d^2 is of less depth than the lower end and hence the latch K' is maintained bearing against the end of the spring k^8 to prevent the latter from forcing the grip J against the wire w . This provides that when the bender-bar H is being raised through its friction connection with the driver-bar D the wire w will not be carried upward from the position to which it has been fed. When, however, the block k of the wire-feed K strikes against the edge of the opening b^8 in the plate B', further upward movement of the bender-bar H is prevented. The driver-bar D, however, still continues to move upward and this brings its lug d^6 into play again causing its beveled side d^7 to act on the beveled lug k^2 of the latch K' to withdraw the latter still further against the action of the spring k^8 . Finally, as the driver-bar approaches the end of its upward stroke its lug d^5 rides out from un-

der the lug k^2 on the latch K' and the latter is allowed to slide to the right, thus permitting the wire-grip J to once more take a bite on the wire w so that the latter will again be fed down to the anvil O at the next downward movement of the bender-bar H . In this way the coördinated parts are operated continuously from the reciprocation of the slide S to form, drive and clench a staple at each rotation of the shaft M .

It will be seen from the foregoing description that my improvement provides for the automatic operation of a plurality of separate stitcher-heads and their associated clencher-devices as a complete, organized machine. Furthermore through the ingenious arrangement for coöordinating the several mechanisms to adapt them to be driven from a single shaft the heads are all adjustable independently to regulate the spacing of the staples and in addition a single, universal adjustment serves to set the several mechanisms as a unit for forming staples of different length in conformity with varying thicknesses of stock being operated upon. In this way my improved apparatus is adapted to a wide variety of work on different types of machines while its productive capacity is greatly increased and its operation rendered more economical.

Various modifications might be made in the construction and arrangement of the parts of the apparatus without departing from the spirit or scope of the invention; therefore, without limiting myself to the exact embodiment shown, what I claim is:—

1. In a wire-stitching or stapling machine, the combination with a plurality of stitcher-heads containing coöordinated staple-forming and driving mechanisms, of means to mount said heads in series, means to connect the mechanisms of the several heads to operate together in unison, a horizontal drive-shaft arranged to reciprocate said connecting-means, and means to adjust said shaft vertically to regulate the position of all of the several mechanisms in the several heads in relation to the work to be stitched.

2. In a wire-stitching or stapling machine, the combination with a plurality of heads carrying separate stitching-mechanisms, of means to mount said heads in series to provide for their lateral adjustment in relation to each other, means connecting the mechanisms of the several heads to operate in unison, a horizontal drive-shaft arranged to reciprocate the connecting-means for the stitching-mechanisms, and means to adjust said shaft vertically to regulate the position of all of the stitching-mechanisms in relation to the work to be stitched.

3. In a wire-stitching or stapling machine, the combination with a plurality of separate stitching-mechanisms, of means for detachably supporting said mechanisms in series,

means for coöordinating the several stitching-mechanisms to operate together, a single driving-means for simultaneously operating the several mechanisms, a crank-shaft for reciprocating said driving-means, and means to adjust said crank-shaft vertically to simultaneously regulate the position of all of the stitching-mechanisms in relation to the work to be stitched.

4. In a wire-stitching or stapling machine, the combination with a plurality of heads carrying separate stitching-mechanisms, of a horizontal rail for supporting said heads in series, clamping-means for attaching the heads at different points along the rail, means adapted to be reciprocated in relation to the rail, means for individually connecting the mechanisms of the heads to be operated from said reciprocating-means, a horizontal drive-shaft for actuating the reciprocating-means, and means to adjust said drive-shaft vertically to regulate the range of action of the stitching-mechanisms in relation to the work being operated upon.

5. In a wire-stitching machine, the combination with a series of stitcher-heads carrying separate stitching-mechanisms, of a single means for operating the several stitching-mechanisms in unison, a crank-shaft for reciprocating said operating-means, and means for adjusting the vertical position of the crank-shaft to simultaneously regulate the operative position of all of the stitching-mechanisms in relation to the work in accordance with the thickness of the stock to be stitched.

6. In a wire-stitching machine, the combination with a series of vertically-operating stitching-mechanisms, of a reciprocable cross-head connected to operate the several stitching-mechanisms, a crank for reciprocating the crosshead, and means to adjust the operative position of the crank to regulate the range of action of the stitching-mechanisms in relation to the work being operated upon.

7. In a wire-stitching machine, the combination with a plurality of separate stitching-mechanisms, of means for supporting said mechanisms in series, reciprocating-means for operating the stitching-mechanisms in unison, a crank-shaft to reciprocate said means, a bearing for said shaft, and means for adjusting said shaft vertically in its bearing to regulate the operative position of the stitching-mechanisms in relation to the work being stitched.

8. In a wire-stitching machine, the combination with a series of separate stitching-mechanisms, of means for regulating their action in conformity with the thickness of the work to be stitched, means for operating the several stitching-mechanisms in unison, and a single means for adjusting the position of all of the stitching-mechanisms in relation to the work and for simultaneously

adjusting their regulating-means in conformity with the thickness of the work.

9. In a wire-stitching machine, the combination with a series of vertically-reciprocable stitching-mechanisms, of a crosshead connected to reciprocate the several stitching-mechanisms in unison, means to reciprocate the crosshead, and means to adjust the position of the reciprocating-means vertically to regulate the operative position of the stitching-mechanisms in relation to the work being stitched.

10. In a wire-stitching machine, the combination with a plurality of heads carrying separate stitching-mechanisms, of a reciprocable crosshead connected to operate the several stitching-mechanisms, means to reciprocate the crosshead, and means to adjust the position of the reciprocating-means vertically in relation to the heads to regulate the range of action of the stitching-mechanisms operating therein.

11. In a wire-stitching machine, the combination with a series of vertically-operating stitching-mechanisms, of a reciprocable crosshead connected to operate the stitching-mechanisms, a crank-shaft connected to reciprocate the crosshead, and means to adjust the crank-shaft vertically in position to regulate the range of action of the stitching-mechanisms in relation to the work being operated upon.

12. In a wire-stitching machine, the combination with a series of vertically-operating stitching-mechanisms, of a reciprocable crosshead connected to operate the stitching-mechanisms, a crank-shaft connected to reciprocate the crosshead, a bearing for the crank-shaft, and adjustable means for raising and lowering the crank-shaft in its bearing to regulate the operative position of the parts connected therewith in relation to the work being operated upon.

13. In a wire-stitching machine, the combination with a series of vertically-operating stitching-mechanisms, of a crosshead connected to operate the stitching-mechanisms, a rotating shaft connected to reciprocate the crosshead, an eccentric bearing for the shaft, and means to turn said bearing to raise or lower the shaft therein to adjust the operative position of the parts reciprocated therefrom in relation to the work being operated upon.

14. In a wire-stitching machine, the combination with vertically-operating stitching-mechanism, of a crosshead connected to operate the stitching-mechanism, a rotating shaft for reciprocating the crosshead, a quill-like bearing in which said shaft is eccentrically mounted, means to turn said bearing to raise or lower the shaft, and means to lock said bearing in place to maintain the shaft in its adjusted position.

15. In a wire-stitching machine, the com-

bination with a vertically-operating stitching-mechanism, of a shaft connected to reciprocate the stitching-mechanism, a quill-like bearing in which said shaft is eccentrically mounted, a handle for rotating said bearing, a sector with which the handle cooperates, and means for locking said handle at different points on the sector to retain the bearing in the position to which it is adjusted.

16. In a wire-stitching machine, the combination with a work-support, of a plurality of stitcher-heads carrying separate stitching-mechanisms arranged above said work-support, means for detachably mounting said heads in series, a reciprocating crosshead formed with a longitudinal groove, means on the several stitching-mechanisms adapted to engage the groove in the crosshead to connect them to be operated therefrom while providing for their lateral adjustment in relation to each other, a crank-shaft for reciprocating the crosshead, and means to adjust the crank-shaft vertically to regulate the position of the stitching-mechanisms in relation to the work-support.

17. In a wire-stitching machine, the combination with a plurality of stitcher-heads carrying separate stitching-mechanisms, of a horizontal rail, means for attaching the stitcher-heads at different points along the rail, a reciprocating crosshead, means on the stitching-mechanisms for connecting them to be operated from the crosshead while allowing for their lateral adjustment therewith, a crank-shaft to reciprocate the crosshead, and means to adjust the crank-shaft vertically to regulate the position of the stitching-mechanisms in relation to the work.

18. In a wire-stitching machine, the combination with a series of stitching-mechanisms for inserting a plurality of staples through the work being operated upon, of a series of cooperating clencher-means for clenching the staples in place as they are inserted through the work, means for adjusting the stitching-mechanisms laterally in relation to each other, means for adjusting the clencher-means in correlation with the stitching-mechanisms, means connected to reciprocate the stitching-mechanisms in unison, a drive-shaft for actuating said reciprocating-means, means to adjust said drive-shaft vertically to regulate the position of the stitching-mechanisms in relation to the clencher-means, and means operated from the crank-shaft to operate the clencher-means in synchrony with the operation of the stitching-mechanisms.

19. In a wire-stitching machine, the combination with a plurality of stitching-mechanisms adjustable laterally in relation to each other, of a plurality of clencher-means for cooperating with the stitching-mechanisms and adjustable in relation therewith,

- a horizontally-arranged crank-shaft connected to operate all of the stitching-mechanisms in unison, means driven from said shaft to operate the clencher-means in synchrony with the operation of the stitching-mechanisms, and means to adjust the crank-shaft vertically to regulate the position of the stitching-mechanisms in relation to the clencher-means.
- 10 20. In a wire-stitching machine, the combination with a stitcher-head carrying vertically - reciprocable wire - feeding staple-forming and staple-driving means, of means to adjust the operative position of the staple-driving means in relation to the work being operated on, and means to simultaneously adjust the range of action of the wire-feeding and staple-forming means to regulate the length of staple in accordance with the thickness of the work.
- 15 21. In a wire-stitching machine, the combination with a stitcher-head comprising vertically-reciprocable means for feeding the wire for forming the staples, means for forming the staples, and means for driving the staples through the work, of means to adjust the operative stroke of the wire-feeding means to regulate the length of the staple and to simultaneously adjust the range 25 of action of the staple-driving means in conformity with the thickness of the stock being operated upon.
- 20 22. In a wire-stitching machine, the combination with a vertically-reciprocable wire-feeding device, a forming-device for forming the wire into staples, a driver for driving the staples through the work, of means to control the stroke of the wire-feed to regulate the length of the staples, and means for adjusting said controlling-means and for simultaneously regulating the range of action of the staple-driver in accordance with the thickness of the work being operated upon.
- 25 23. In a wire-stitching machine, the combination with a fixed work-support, of a stitcher-head mounted above the work-support, stitching-mechanism reciprocable vertically in the stitcher-head comprising wire-feeding, staple-forming and staple-driving devices, and means to adjust the range of action of the wire-feeding, staple-forming and staple-driving devices in relation to the work-support to regulate the length of the staple and its insertion through the work in conformity with the thickness of the stock being operated upon.
- 30 24. In a wire-stitching machine, the combination with a fixed work-support, of a stitcher-head mounted above said support, wire-feeding and staple-forming devices vertically reciprocable in the stitcher-head to form the staples, a staple-driver also reciprocable in the head to drive the staples through the work, means to reciprocate said
- wire-feeding, forming-devices and staple-driver, and means to adjust their range of action to regulate the forming and driving of the staple in accordance with the thickness of the stock being operated upon.
- 35 25. In a wire-stitching machine, the combination with a stitcher-head, of a wire-feeding device vertically reciprocable in said head, a staple-former also reciprocable in the head, a reciprocable staple-driver, means to adjust the stroke of the wire-feeding device to regulate the length of the staple, and means to simultaneously adjust the stroke of the staple-driver in accordance with the thickness of the stock being operated upon.
- 40 26. In a wire-stitching machine, the combination with a stitcher-head, of a staple-former reciprocable therein, a wire-feed on the staple-former, a reciprocable staple-driver, means to reciprocate said staple-former and driver, means to adjust the length of stroke of the wire-feed to regulate the length of the staple, and means to adjust the range of action of the staple-driver in relation to the work, both of said adjusting-means being operable in unison in accordance with the thickness of the work being operated upon.
- 45 27. In a wire-stitching machine, the combination with a reciprocable slide, of means to adjust the range of action of the slide, a driver-bar reciprocated from the slide, a staple-driver on said bar, a bender-bar adapted to be driven through frictional engagement with the driver-bar, a wire-feed on the bender-bar, an anvil co-operating with the bender-bar to form the staple, and means to control the stroke of the bender-bar to regulate the action of the wire-feed in accordance with the length of staple required.
- 50 28. In a wire-stitching machine, the combination with a reciprocable slide, of a bender-bar reciprocated from the slide, means co-operating with the bender-bar to form the staple, a staple-driver also reciprocated from the slide, a wire-feed reciprocable with the bender-bar, means to adjust the operative length of stroke of the wire-feed to regulate the length of the staple, and means to simultaneously adjust the range of action of the driver in accordance with the thickness of the work being stapled.
- 55 29. In a wire-stitching machine, the combination with a reciprocable slide, of a sliding-bender-bar reciprocated from said slide, a wire-feed on the bender-bar, means co-operating with the bender-bar to form the staple from the length of wire fed thereby, means to adjust the operative length of stroke of the wire-feed, a staple-driver reciprocated from the slide, and means to adjust the range of action of the staple-driver in accordance with the thickness of the work being operated upon.

30. In a wire-stitching or stapling machine, the combination with a reciprocable bender-bar, of means coöperating therewith to form the staple, a wire-feed carried by 5 the bender-bar and acting to grip and feed the wire throughout its movement with the bender-bar, means to limit the stroke of the wire-feed, means to release the grip of the wire-feed on the wire, and means to adjust 10 the stroke limit for the wire-feed and to simultaneously adjust the grip-releasing means.

31. In a wire-stitching or stapling machine, the combination with a reciprocating bender-bar, of a wire-feed reciprocable therewith, means coöperating with the bender-bar to form the staple from a length of wire fed by the wire-feed, means to adjust 15 the stroke of the wire-feed, adjustable 20 means to release the wire-feed from the wire at one end of its stroke, and means to control said stroke-adjusting means and said wire-feed releasing-means in unison.

32. In a wire-stitching or stapling machine, the combination with a reciprocating bender-bar, of a wire-feed reciprocable therewith, means coöperating with the bender-bar to form the staple from a length of wire fed by the wire-feed, means engaged by 25 the wire-feed to limit its stroke in one direction, means engaged by the wire-feed to release it from the wire during its movement in the opposite direction, and means to adjust said stroke-limiting means and releasing-means in unison to regulate the 30 length of wire fed by the wire-feed.

33. In a wire-stitching or stapling machine, the combination with a bonnet, of a bender-bar reciprocable in said bonnet, a wire-feed reciprocable with the bender-bar, means coöperating with the bender-bar to form the staple from the wire fed by the wire-feed, a plate adjustable on the bonnet to control the length of stroke of the wire-feed, means adjustable on the bonnet to release the wire-feed from the wire at one end 45 of its stroke, and means connecting said plate and said releasing-means to adapt them to be adjusted in unison.

34. In a wire-stitching or stapling machine, the combination with a reciprocable slide, of a bender-bar reciprocated from said slide, a rotatable anvil for coöperating with the bender bar to form the staples, a rotatable hub, means on the slide for rotating the hub from the reciprocatory motion thereof, a crank on the hub, and means connecting the crank with the anvil to rotate the latter during the descent of the bender-bar.

35. In a wire-stitching or stapling machine, the combination with a reciprocable slide, of a bender-bar reciprocable from said slide, a rotatable anvil for coöperating with the bender-bar to form the staples, a hub

rotated from the movement of the slide, a 65 crank on said hub, and a link connecting said crank with the anvil to impart rotation thereto.

36. In a wire-stitching or stapling machine, the combination with a reciprocable 70 slide, of a hub rotated from the movement of the slide, a crank-pin on said hub, a rotatable forming-anvil, means to mount said anvil to adapt it to slide longitudinally of its axis, a bender-bar reciprocated from the 75 slide to coöperate with the anvil to form the staples, and a spring-link arranged to connect the anvil with the crank-pin on the hub to cause it to be rotated therefrom and to press upon the anvil during its rotation 80 to control its position in relation to the bender-bar.

37. In a wire-stitching machine, the combination with a plurality of stitcher-heads, 85 of means to mount said heads in series, wire-feeding devices in each head, staple-forming and driving devices in each head, means for simultaneously adjusting the range of action of the several wire-feeding devices to regulate the length of the staples, means for operating the staple-forming and driving devices of the several heads in unison, and means for adjusting said operating-means to regulate the operative position of all of 90 the staple-forming and driving devices, said 95 means connected to operate the adjusting-means for the wire-feeding devices.

38. In a wire-stitching machine, the combination with a plurality of stitcher-heads, 100 of staple-forming and driving devices in each head, wire-feeding devices in the several heads, a single operating-means for all of the heads, means for adjusting said operating-means to regulate the operative position of all of the staple-forming and driving devices in relation to the work to be stitched, and means connected with said adjusting-means for simultaneously controlling the 105 action of the several wire-feeding devices to regulate the length of the staples in conformity with the thickness of the work.

39. In a wire-stitching machine, the combination with a plurality of stitcher-heads, 110 of staple-forming and driving devices in each head, wire-feeding devices in the several heads, a single operating-means for all of the heads, means for adjusting said operating-means to regulate the operative position of the several staple-forming and driving devices in conformity to the thickness of the stock to be stitched, and means connected therewith to be adjusted therefrom for controlling the action of the wire-feeding means to regulate the length of the staples.

40. In a wire-stitching or stapling machine, the combination with a reciprocating bender-bar, of a wire-feed reciprocable

therewith, an anvil coöperating with the bender-bar to form the staple from a length of wire fed by the wire-feed, means engaged by the wire-feed to limit its stroke in one direction, means engaged by the wire-feed to release it from the wire during its stroke in the opposite direction, and means for adjusting the position of the wire-feed stroke-limiting means and releasing-means in relation to the forming-anvil.

41. In a wire-stitching machine, the combination, with a vertically reciprocating bender-bar, of means coöperating therewith to form the staple from a length of wire fed thereto, a staple-driver for driving the staple through the work, a staple-supporter pivoted on the bender-bar to adapt it to move into position between the legs of the formed staple, and means for controlling the action of the staple-supporter to allow it to move into operative position as the bender-

bar descends and to retract it from said position as the bender-bar moves upward.

42. In a wire-stitching machine, the combination with a vertically reciprocating bender-bar, of means coöperating therewith to form the staple from a length of wire fed thereto, a staple-driver for driving the staple through the work, a staple-supporter pivoted on the bender-bar to adapt it to move into position between the legs of the formed staple, means for controlling the action of the staple-supporter to allow it to move into operative position as the bender-bar descends and to retract it from said position as the bender-bar moves upward, and resiliently-operated means adapted to engage the staple-supporter to yieldingly maintain it in its operative position.

In testimony whereof I affix my signature. 40

ARTHUR H. MAYNARD.
